UNITED STATES PATENT OFFICE

166,516

WINDMILL KNIFE HOLDER

Bernard Yellin, Chicago, Ill.

Application January 5, 1952, Serial No. 17,949

Term of patent 14 years

(Cl. D44—29)

To all whom it may concern:

Be it known that I, Bernard Yellin, a citizen of the United States, and a resident of the city of Chicago, county of Cook, State of Illinois, have invented a new, original, and ornamental Design for Windmill Knife Holder, of which the following is a specification, reference being had to the accompanying drawing, forming a part thereof in which:

Figure 1 is a front elevation view of a windmill knife holder, showing my design;

Figure 2 is a side view of the windmill knife holder shown in Figure 1 taken from the right of Figure 1;

Figure 3 is a top view of the windmill knife holder shown in Figure 1 taken from above Figure 1;

Figure 4 is a front isometric view of the windmill knife holder; and

Figure 5 is a rear isometric view of the windmill knife holder.

I claim:

The ornamental design for a windmill knife holder, substantially as shown.

BERNARD YELLIN.
